VELOCIPED FRAME

Raymond M. Krokos, Detroit, Mich., assignor to Evans Products Company, Plymouth, Mich., a corporation of Delaware

Filed Mar. 11, 1960, Ser. No. 59,693

Term of patent 14 years

(Cl. D34—15)

FIGURE 1 is a perspective view of a velocipede frame showing my new design;

FIGURE 2 is a plan view thereof;

FIGURE 3 is a side elevation thereof;

FIGURE 4 is a front elevation thereof; and

FIGURES 5 and 6 are sectional views thereof taken respectively, along the lines 5—5 and 6—6 of FIGURE 3.

The essential feature of the design is the combination of a main frame member of oval cross section with a wishbone frame member of circular cross section.

I claim:

The ornamental design for a velocipede frame, as shown and described.
